UNITED STATES PATENT OFFICE.

ELLIS E. LOWELL, OF WOODSTOCK VALLEY, CONNECTICUT.

FLUE-CLEANER.

1,196,467.

Specification of Letters Patent. Patented Aug. 29, 1916.

Application filed May 3, 1916. Serial No. 95,066.

To all whom it may concern:

Be it known that I, ELLIS E. LOWELL, a citizen of the United States of America, residing at Woodstock Valley, in the county 5 of Windham and State of Connecticut, have invented a new and useful Flue-Cleaner, of which the following is a specification.

My invention relates to improvements in expansive cleaners for the flues or tubes of 10 boilers and the like, and consists of a certain peculiar frame, two pairs of segmental scrapers, those in each pair being spaced apart and having their cutting or scraping edges juxtaposed to the corresponding edges 15 of those in the other pair, but in offset relation thereto, a brush interposed between the scraping edges of the two pairs of scrapers, and means to expand and contract said scrapers, together with such auxiliary and 20 subsidiary parts and members as may be needed to render the cleaner complete and serviceable.

The primary object of my invention is to produce a strong, durable, and convenient, 25 yet comparatively simple and inexpensive flue or tube cleaner, which can be operated as effectually in one direction as the other, has resilient scrapers that yield to obstructions, can be adjusted, that is, expanded or 30 contracted, while within a flue or tube as well as when outside of the same, and in combination make up with their scraping edges a complete circle the diameter of which is equal or approximates that of the 35 bore which said edges fit, to the end that not only is a longitudinal movement of the cleaner alone without any rotary movement, all that is required to scrape and clean out a flue or tube, but the necessity is avoided 40 of withdrawing the cleaner from the bore, partially rotating the same, and then reintroducing it into said bore.

Other objects and advantages will appear in the course of the following description. 45 I attain the objects and secure the advantages of my invention by the means illustrated in the accompanying drawings, in which—

Figure 1 is a side elevation of a flue cleaner that embodies a practical form of 50 my invention; Fig. 2, a longitudinal central section through said cleaner, and, Fig. 3, a cross-section through the cleaner, taken on lines 3—3, looking in the direction of the 55 associated arrow, in Fig. 1.

Similar reference numerals refer to similar parts throughout the several views.

The cleaner illustrated in the drawings, comprises a frame which carries a plurality of resilient scrapers 1; a shaft or spindle 2 journaled in said frame, and a circular brush 4 mounted on said spindle between adjacent ends of endwise oppositely-disposed scrapers, as will presently be more fully explained.

The aforesaid frame consists of two end or head blocks 5, in which the shaft 2 is journaled, and a plurality of tie-rods 6. Generally there are two tie-rods 6. The latter have their ends rigidly attached to the blocks 5. Said tie-rods at one extremity are secured to opposite sides of the head block at that end, and at the other extremity are secured to opposite sides of the corresponding head block, but to sides that are out of line with said first-mentioned sides. To enable the above-mentioned attachments to be made, the tie-rods 6 are bent as shown at 7.

Preferably there are four scrapers 1 arranged in pairs on opposite sides of the transverse center of the frame, with the scrapers in each pair relatively oppositely disposed laterally of the device, and those in the two pairs relatively oppositely disposed longitudinally of said device. In consequence of this the head blocks 5 are rectangular in cross-section, in order to provide a side for each scraper 1 and a side for one end of each tie-rod 6. Projecting from each side of each block 5 is a screw-threaded stud 8. The ends of the tie-rods 6 are provided with eyes or loops which are passed over four of the studs 8 and thereon rigidly secured by means of nuts 9, the latter being screwed on to said studs and binding the looped portions of said tie-rods tightly against the contiguous sides of the blocks 5. The outer terminal portions of the scrapers are perforated to receive the studs 8, and such portions are placed over such studs as are unengaged by the tie-rods 6, and there secured and tightly held against the contiguous sides of the blocks 5 by nuts 10 screwed on to said studs.

A frame is thus provided for the spindle 2 and the scrapers 1, which though simple is sufficiently strong and rigid.

The scrapers 1 are resilient, and each has at its inner end a segmental scraping edge, 110

blade, or cutter 11, which is the part that does the actual work of removing the deposits from the interior surfaces of tubes. Each cutter 11 is equal approximately to a ⁵ fourth of a circle, so that as arranged the four cutters form a complete although not continuous circle. All parts except the outer terminals of the scrapers 1 are clear of the head blocks 5, and the scrapers flare out- ¹⁰ wardly from the longitudinal center or axis of the device and beyond the blocks 5. In the center approximately of each scraper 1 is a longitudinal slot 12.

The spindle 2 extends beyond the blocks ¹⁵ 5 and is screw-threaded at the terminals. Two bell-shaped guards 13 are screwed on to the protruding terminals of the spindle 2, and are held in place by check-nuts 14-14. The guards 13 are not set up against the ²⁰ adjacent ends of the blocks 5, because if they were they would bind on the blocks and so interfere with the rotation of the spindle 2, but said guards, nevertheless, practically hold said spindle against endwise movement ²⁵ in said blocks. The guards 13 protect the cleaner at the ends, and facilitate the introduction of the cleaner into a tube at either end.

At one end, it being immaterial which, the ³⁰ spindle 2 has a projection sufficient to receive a coupling 15 for a long pipe or rod 16, by means of which latter the device is actuated back and forth in and through a tube, such rod being in fact a handle for the cleaner. The major portion of the rod 16 is broken off in the first two views where such rod appears.

The spindle 2 has right- and left-hand ⁴⁰ screw-threads 17 and 18 thereon adjacent to the blocks 5 or respectively between said blocks and the brush 4, which latter is loosely mounted on said spindle between adjacent ends of the oppositely-disposed pairs of scrapers 1, or between the two planes each ⁴⁵ of which is common to the cutters 11 in each pair.

The brush 4 is not thick enough to interfere at any time with the scrapers 1, and the diameter of said brush approximates that ⁵⁰ of the bore of a tube which the cleaner is designed to fit. Preferably the flexible members of the brush are of wire. The tie-rods 6 pass through the aforesaid flexible members and so prevent the brush from rotating ⁵⁵ on the spindle 2. The brush is held against endwise movement on the spindle by any suitable means, as a screw 19 set in the body of said brush and extended into an annular groove 20 in said spindle.

⁶⁰ The office of the brush 4 is to remove from a tube the particles detached therefrom by the scrapers 1, and said brush like said scrapers operates in either direction.

Collars 21-21 are tapped onto the ⁶⁵ threaded parts 17 and 18 of the spindle 2.

Screws 22-22 are passed through the slots ⁷⁰ 12, in the scrapers 1 in each pair, and tapped into the collar 21 between such scrapers. The heads of the screws 22 limit the outward flare or extension of the otherwise uncon- ⁷⁵ fined portions of the scrapers 1 from the axis of the device.

It will now be seen that, when the spindle ² is rotated in one direction, the collars 21 are caused to approach each other, and the scrapers 1 are drawn inwardly or contracted, and, when said spindle is rotated in the opposite direction, said collars are caused to recede from each other, and said scrapers are permitted to move outwardly or expand, ⁸⁰ the screws 22 moving in the slots 12 in each case. By this means and in this manner the scrapers are adjusted to fit a tube, and to adapt them to meet the conditions existing in such tube, since the scrapers can be adjusted while the cleaner is in a tube as well as before the former is introduced into the latter.

The screws 22 in each collar 21 are diametrically opposite to each other, and peripheral transverse grooves 23-23, diametrically opposite to each other and between said screws, are formed in said collar. The tie-rods 6 pass through the grooves 23 and so hold the collars 21 against rotation ⁹⁰ and take the strain from the screws 22 when the spindle 2 is rotated. The collars 21, when actuated by the screw-threaded portions 17 and 18 of the spindle 2, slide between the tie-rods 6 with the latter in the ⁹⁵ grooves 23 to guide and hold said collars against rotation, as previously stated.

This cleaner is operated like flue cleaners generally by being forced back and forth through the tube being scraped to remove ¹⁰⁵ therefrom the scale and other accumulation of foreign matter therein, the amount of expansion of the scrapers 1 and the force exerted circumferentially by the cutters 11 on the sides of said tube being determined and ¹¹⁰ regulated in the manner hereinbefore explained at length.

With this device tubes can be cleaned thoroughly and expeditiously.

Minor changes in matters of shape, size, ¹¹⁵ arrangement, and construction of the parts of my cleaner may be made without departing from the spirit of my invention.

What I claim as my invention, and desire to secure by Letters Patent, is—

1. The combination, in a flue cleaner, with a frame comprising head blocks, and tie-rods rigidly attached at their ends to opposite sides of said blocks, laterally of the cleaner, such sides being out of line with ¹²⁵ each other, longitudinally of the cleaner, of scrapers attached to the sides of said blocks that are between the sides to which said tie-rod are attached.

2. The combination, in a flue cleaner, with ¹³⁰

- a frame comprising head blocks, and tie-rods rigidly attached at their ends to said blocks, of a right- and left-hand screw-threaded spindle journaled in said blocks,
- 5 **6** resilient slotted scrapers attached to said blocks, collars mounted on said screw-threaded portions of said spindle, said collars being engaged by and in sliding relation to said tie-rods, and headed members
- 10 **10** passing through the slots in said scrapers into said collars.
3. The combination, in a flue cleaner, with a frame comprising head blocks, and tie-rods rigidly attached at their ends to said
- 15 **15** blocks, of a right- and left-hand screw-threaded spindle journaled in said blocks, resilient slotted scrapers having segmental scraping edges, said scrapers being attached to said blocks and arranged with said scraping edges in two planes spaced apart and approximately at right-angles to the axis of
- 20 **20** the cleaner, collars mounted on said screw-threaded portions of said spindle, said collars being engaged by and in sliding relation to said tie-rods, headed members pass-
- ing through the slots in said scrapers into said collars, a brush on said spindle between said planes, said tie-rods passing through said brush, and means to hold said brush against endwise movement on said spindle. 30
4. The combination, in a flue cleaner, with a frame comprising head blocks, and tie-rods rigidly attached at their ends to opposite sides of said blocks, laterally of the cleaner, such sides being out of line with 35 each other, longitudinally of the cleaner, of two pairs of resilient scrapers having segmental scraping edges, such scrapers being attached to the sides of said blocks that are between those to which said tie-rods are attached, and arranged with said scraping edges in two planes spaced apart and approximately at right-angles to the axis of the cleaner, and expanding and contracting means, carried by said frame, for said 40 scrapers.
